POWER SHOVEL DIPPER DOOR LATCH

Cecil E. Jones, Lima, Ohio

Application March 14, 1942, Serial No. 434,653

5 Claims. (Cl. 292—186)

This invention relates to latch mechanism for the dumping door of a dipper, such as is used on power shovels and like equipment.

Ordinarily, a dipper door latch is adapted to be released by a power device which pulls a trip cable operating through leverage so as to withdraw the latch from the latch keeper, thereby permitting the door to open and the load to be dumped, for instance into the dump body of a truck. Because of the considerable weight of the load of material in the dipper, especially in dippers of large capacity, a very considerable force is required to release the latch. In many cases, even through the power-driven device, known as a "dipper trip," is employed, the required force has been so great that compound or multiple lever systems have been used in the latch operating mechanism, in order to give an increased mechanical advantage. In some instances, a supplemental lever was arranged toward the bottom of the dipper stick, and in other cases such a supplemental lever was mounted on the bottom of the dipper door itself.

The foregoing expedients have proven troublesome and disadvantageous from a number of standpoints, including the fact that the installation of multiple levers is cumbersome, provides more points for clogging with mud and freezing with water, and has resulted in excessive failures. Fouling of the operating mechanism on the sides of dump bodies on trucks has also occurred.

One of the problems which has been encountered in connection with the foregoing is that the available space on the dipper door for the mounting of operating parts is relatively limited, when considering the degree of mechanical advantage required from the operating leverage.

The present invention is particularly directed to the problems referred to above and, in accordance with the invention, a single operating lever is employed, this lever being arranged to provide the required high degree of pull for withdrawing the latch.

The operating mechanism of this invention, including said single lever, may readily be installed in the limited space available on the bottom of the dipper door, in a protected position; and the invention also contemplates a mounting bracket for the parts, configured to shield moving surfaces from mud and the like.

In accordance with another aspect of the invention, the several parts of the operating mechanism are arranged so as to permit the use of relatively large fulcrum pins in a very confined

space, thereby providing a construction which is not only rugged, but which wears only very slowly.

A further object of the invention is the provision of a novel means for adjusting the position of the latch with reference to the operating lever, this mechanism being constructed to facilitate the making of adjustments, as will further appear.

Another purpose of the invention is to so form and mount the operating lever and other parts as to provide proper latch closure by gravity, even without the aid of the usual closure spring.

The invention also contemplates arrangement of the operating leverage for the latch in a manner providing different degrees of mechanical advantage as between different parts of the stroke from latch-engaged to latch-release position. In accordance with this feature, the mechanical advantage is at a maximum in the initial portion of the release movement of the latch, the succeeding and latter portion of the movement affording a somewhat reduced mechanical advantage but providing a higher speed of release movement. This feature is of particular importance because of the fact that the force required to withdraw the latch from the latch keeper is at a maximum at the start of the stroke, and thereafter diminishes. Therefore, the total throw of the single operating lever need not be excessively long, notwithstanding the fact that an unusually high mechanical advantage is provided for the initial portion of the release stroke.

In accomplishing the foregoing, the invention contemplates the employment of a lever member and a link member pivotally interconnected, a latch bar, a pivotal connection between one of said members and said bar, and a fulcrum for the other of said members, so that when the mechanism is operated one of the pivots moves in an arc about the fixed center of the fulcrum, thereby accommodating the swinging motions of said members to the rectilinear motion of the latch bar. This arrangement also has the advantage of giving the desired variation in leverage at different parts of the releasing stroke. The invention also provides means of adjustment of the geometrical relationship of certain of these parts, for example an adjustment in the effective length of the link member, whereby to provide for various desired initial positions of latch bar and lever member, etc., or to compensate for wear. This can be utilized to adapt the mechanism to different dippers and different doors; but when once mounted on a door, normal adjustments for wear can be made at the link member in such

a way as to shift the position of the latch bar relative to the operating lever, without shifting the position of said lever or its fulcrum, so that this lever will move between the same limits of throw and can, therefore, make full surface contact with the limiting stops, under different conditions of adjustment.

How the foregoing and other objects and advantages are attained will appear more fully from the following description, referring to the accompanying drawings, in which—

Figure 1 is a bottom view of a dipper door with the improved latch operating mechanism of this invention applied thereto;

Figure 2 is an enlarged view of the latch operating mechanism as shown in Figure 1;

Figure 3 is a view taken substantially as indicated by the line 3—3 on Figure 2;

Figure 4 is a view taken substantially as indicated by the line 4—4 on Figure 2; and

Figures 5 and 6 are fragmentary sectional views of details taken substantially as indicated by the lines 5—5 and 6—6, respectively, on Figure 1.

The dipper door plate appears at 6, this plate having reinforcements such as indicated at 7, 8 and 9—9, the latter being extended beyond one edge of the door to serve as hinges 10—10 by means of which the door is pivotally connected to the dipper.

The latch bar 11 extends through guides such as indicated at 12, providing for sliding movement of the latch bar in a direction generally transverse to the lower edge of the door, the latch bar (when in engaged position) usually projecting beyond the edge of the door, so as to cooperate with a keeper mounted on the dipper. As seen in Figure 3, the latch bar 11 is weighted by thickening, so as to aid in latching by gravity, and this thickening is on the face of the bar toward the dipper door plate 6, so that a space is left for the inner arm of the clevis 19 and for the insertion of a cotter pin through the inner end of pivot 20.

The operating lever for the latch appears at 13, this lever being bifurcated at one end to provide a pair of prongs 14—14 which are received between upper and lower plates 15—15 of a mounting bracket which is secured to the door plate 6. A pivot pin 16 serves to pivotally interconnect the lever and the mounting bracket, the pin being retained in position by means of a cotter 17 overlying the head of pin 16 and mounted in a boss 17a on the outer bracket plate 15.

It should be observed that the space between the plates 15—15 of the mounting bracket is closed on two sides, as indicated at 15a—15a. The side walls on these two sides cooperate with the plates 15—15 to provide a closed pocket housing and protecting the pivot parts including pivot 16 already described, as well as other pivot parts mentioned herebelow.

Movement of the lever may be effected by the usual trip cable which may be connected with the free end of the lever by means of the apertured lug 18. This lug is located at the upper face of the lever and toward its outer face, so that (as seen in Figures 2 and 4) there is clearance for attaching the cable without fouling on the door plate 6. The lever 13 itself is weighted by thickening on its inner face, as shown, in a region adjacent the cable attachment lug, which assures downward swinging of the lever, even in the absence of a latch closure spring, when the door is in a pendent position such as illustrated

in Figure 1. This weighting of the lever is sufficient to overcome the automatic tension which is normally imposed upon the trip cable by the power dipper trip to keep slack out of said cable at all times.

The latch bar 11 is coupled with the lever 13 by means of a link 19 having a pivotal connection 20 with the latch bar. The pivot 20 passes through an elongated slot 20a formed in the latch bar, so that the latch may give when the door closes, without requiring raising of the operating lever 13.

The link 19 is internally threaded to receive the threaded eye bolt 21, these parts being fixed in position relative to each other by a lock nut 22. The eye of said bolt 21 projects between the prongs 14—14 of the bifurcated end of lever 13, the parts being joined by a pivot pin 23. This pin is desirably retained in position by virtue of extension of plates 15 of the lever mounting bracket, as indicated at 24.

Swinging movement of the operating lever may be guided by means of a strap 25 secured to blocks 26 which serve as stops limiting the throw of the lever. These stops are configured to have extended surface contact with the thickened (weighted) portion of lever 13, which extended contact is the same under all conditions—thereby reducing wear at the contact surfaces—because there is no change in the throw of the lever or the point of its fulcrum due to normal adjustments of the latch, as will now appear.

Adjustment of the latch may be effected by withdrawing pin connection 20 between latch bar 11 and link 19, whereupon the link 19 may be swung to one side as indicated at 19a, in which position the lock nut 22 is loosened and the link rotated about its threaded connection with the eye bolt 21. As will readily be seen, this will alter the position of the latch bar with reference to the operating lever, and this mechanism may be used when it is desired to compensate for wear of any of the latch or operating parts, or of the latch keeper.

More extensive adjustments of this latch assembly can be employed, if desired, to alter the initial positions of the latch bar and operating lever, so as to suit installation on different doors.

Before considering the action of the operating lever and link, it is pointed out that the mechanism is compact and readily adapted to fit in the limited space available on the bottom of the door between the various reinforcing members and other parts, such as the reinforcing bar 28 and the stop bracket 27, which latter serves as an abutment limiting opening movement of the door. Stop bracket 27 projects appreciably from the plane of the door plate whereas the latch operating mechanism does not project appreciably therefrom, in view of which the parts are well protected and will not undesirably foul on dump bodies of trucks or the like.

In considering the operation of the mechanism, it is first pointed out that because of the usual position of the dipper and of its door, when the operator swings the dipper to close the door, gravity may be relied upon to move the lever 13 and the latch bar 11 downwardly into latch-engaged position. This is the full line position of Figures 1 and 2.

In Figure 2, the dot-and-dash line 13a of the operating lever represents the latch-release position, as effected under the influence of the trip cable (not shown). Examination of Figure 2 will show that when the lever 13 is in latch-engaged

position, the axis p of pivot 23, interconnecting lever 13 and link 19, is located close to, though preferably just to the right of, line $x-x$ representing the path of movement of the latch bar 11. When the lever is moved to the latch-release position, this pivot axis moves to the point indicated at p' .

During the movement from latch-engaged to latch-release position, the mechanical advantage is altered, being greatest in the latch-engaged position and at a minimum in the release position. The different mechanical advantages in the pull on link 19 have the ratio illustrated by distances y and z , which are the effective lever arms, respectively, of points p and p' from the axis of pivot 16.

It may also be noted that as the release position is approached, the actual path of movement of the link 19 approximates tangency with the arc described by the axis of pivot 23 when moving from the position indicated at p to the position indicated at p' .

The structure as illustrated further has the following advantage. Since point p is located slightly to the right of line $x-x$, and point p' slightly to the left of that line, the link 19 is always maintained approximately in alignment with the path of movement $x-x$ of the latch bar 11. The direction of pull on the latch bar, therefore, is always very close to the line $x-x$.

The difference between the mechanical advantage in different portions of the stroke of the operating lever may be altered by differently locating the axis of pivot 16, so as to change the ratio represented by the distances y and z . Differences in effect may also be secured by differently locating the axis of pivot 23 with reference to pivot 16, or with reference to the line $x-x$.

The preferred arrangement contemplates that when the parts are in latch-engaged position, not only is the lever arm from pivot center 23 to fulcrum 16 at its maximum leverage (i. e., the minimum effective distance y); but so also (or nearly so) is the lever arm of the lever 13 (represented by a line joining the lug center 18 and the fulcrum center 16), for the latter is then approximately perpendicular to the line of cable pull and to the line of pull upon the latch (which thus gives substantially the maximum effectiveness). In the release position, when the first-mentioned lever arm is at its minimum operating effectiveness (represented by the increased distance z), the effective leverage of the arm between centers 18 and 16 is then also a minimum. In short, one lever arm has an angular lag with relation to the other (as in a bell-crank), and they are so disposed that their varying leverages co-act in the intended sense. At the same time, pivot pins of increased diameter can be employed, because, even though this requires increased distance between pivot centers (of pins 16 and 23), a more than compensatory increase in overall effective leverage at the commencement of the stroke is secured.

I claim:

1. For a dipper door latch assembly, a latch bar operating lever having a transverse pivot axis adjacent one end, about which the lever may swing downwardly by gravity when the dipper door is in a pendent position, actuating attachment means adjacent the other end of the lever, and weighting means on the lever near said attachment means, said weighting means being configured to form extended surfacing for abutment against complementary limiting stop means, whereby the weighting means serves also as a wear element.

2. In latch mechanism for dipper doors, the combination of a latch bar movable generally transversely of an edge of the door, a latch bar operating lever adapted to be operated to release the latch bar by an actuating cable connection or the like movable in a path generally paralleling the path of movement of the latch bar, means mounting the lever for angular movement through a range in which the mid-position is substantially perpendicular to the path of movement of the latch bar, and a pivotal connection between the lever and the latch bar comprising a pivot angularly movable with the lever in an arcuate path in which the mid-position is angularly offset from the mid-position of the lever to provide a substantial component of the initial portion of the release movement of the pivot in a direction transverse the path of the latch bar, while the major component of the final releasing movement of said pivot is substantially parallel to said path of the latch bar.

3. A construction in accordance with claim 2 in which the pivotal connection between the lever and the latch bar further comprises a link having a pivotal connection with the latch bar to accommodate the component of movement of said first pivot in a direction transverse the path of the latch bar.

4. A construction in accordance with claim 2 in which the pivotal connection between the lever and the latch bar further comprises a link one end of which is pivotally connected with the lever by said first mentioned pivot, and a second pivot interconnecting said link and the latch bar, said two pivots having their axes parallel to each other to accommodate the component of movement of said first pivot in a direction transverse the path of the latch bar.

5. For a dipper door latch assembly, a latch bar, an operating lever having a transverse pivot axis adjacent one end, about which the lever may swing downwardly by gravity when the dipper door is in a pendent position, actuating attachment means adjacent the free end of the lever, pivot means connecting the latch bar with the operating lever at a point nearer to the pivoted end of the lever than to the free end thereof, and weighting means on the lever concentrated at a point nearer to the free end thereof than to the pivoted end thereof.
